UNITED STATES PATENT OFFICE.

TIMOTHY J. O'TOOLE, OF BROOKLYN, NEW YORK.

IMPROVEMENT IN STREET-RAILWAYS.

Specification forming part of Letters Patent No. 148,238, dated March 3, 1874; application filed January 30, 1874.

To all whom it may concern:

Be it known that I, TIMOTHY J. O'TOOLE, of Brooklyn, in the county of Kings and State of New York, have invented certain new and useful Improvements in Street-Railways; and I do hereby declare the following to be a full, clear, and exact description of the invention, such as will enable others skilled in the art to which it pertains to make and use it, reference being had to the accompanying drawings, which form part of this specification, in which—

Figure 1 is a side elevation of my improvement. Figs. 2 and 3 are transverse sectional views, illustrating different methods of carrying my invention into effect.

This invention has relation to railways designed especially for use in cities of large population; and consists essentially in the combination, with a railway located upon the ground, of an elevated track, upon which run an engine and trucks connected with the cars beneath, as hereinafter described.

Heretofore, as is well known, the power for propelling or drawing street and other cars has usually consisted of an engine running on the same track as the cars. With my improvement the engine or other apparatus for communicating locomotion to the cars runs upon an elevated track, drawing after it upon the same track a series of light trucks or frames on wheels. These trucks or frames are connected, by hangers or equivalent arms or braces, with the car or cars beneath, running upon a track or tracks on the ground, so that when the engine is moved the cars will be drawn along on the track beneath.

Referring to the accompanying drawing, which illustrates my invention, A A are the two tracks of a street-railway. Between these two tracks are erected posts or pillars B B, supporting beams C C, from which depend hangers D. E E are rails, suitably affixed to these hangers, upon which run an engine, F, and a train (one or more) of light trucks or frames on wheels G. H H show hangers, connecting the trucks G with the car or cars H' below, the connection being of that nature that said cars may be readily attached to and detached from each other when necessary or desirable.

In carrying this invention into effect the street-cars may run on double wheels, as at present, with a truck mounted on a single line of wheels overhead, or will run on one wheel constructed especially for the purpose below, while the trucks overhead have one or two wheels. The advantage of having only one below is, that it will relieve the street of two rails.

The above improvements have reference particularly to a need of the present day—namely, rapid transit at a cheap rate from the heart and thickly-settled portions of large cities to the suburbs and surrounding rural districts. My improvements afford a solution of this problem of rapid transit.

In carrying my invention into effect, there shall be upper wheels attached to the cars by an easy contrivance—two, if there be but one below; one, if there be two below. These wheels shall be so adjusted as to secure safe and steady motion for the cars at any speed. In fact, no car can well jump the track with this arrangement.

Cars for this line may be of different sizes to suit the demand for transfer to the different stations at which they will require to stop. In this respect it is plain that, starting from either end of the route, it will be necessary to have these trains make but two or three stops to take up passengers. This can be accomplished without delay by having cars awaiting the train, ready for attachment, which can be done under favorable circumstances without coming to a dead stop.

The proposed overhead road for driving power, while it will be perfectly strong and capable of the work it has to do, will manifestly need no very heavy or massive structure in the center of the street. The upright iron columns will rise between the two tracks, and need not be more frequent than every forty feet at the least. They will be, of course, high enough to avoid all interference with ordinary street traffic. The hangers to support the upper rails may be dispensed with, if desired, and the latter supported directly upon the transverse beams C, in which case the devices for connecting the cars upon the street with the trucks above will be so constructed and arranged as to avoid the ends of said trans-

verse beams, and yet have connection with both cars and trucks when they are located in the same vertical plane, as shown in Fig. 3 of the accompanying drawings.

I claim—

The combination, with the ground-track A, supporting the passenger-cars H, of the elevated railway supporting the traveling engine, said cars and engine being coupled to-

gether, substantially as and for the purpose specified.

In testimony that I claim the foregoing I have hereunto set my hand this 23d day of January, 1874.

TIMOTHY J. O'TOOLE.
